UNITED STATES PATENT OFFICE.

JAN LORENC, OF PHILADELPHIA, PENNSYLVANIA.

SHIP-BUFFER.

1,250,604.

Specification of Letters Patent. Patented Dec. 18, 1917.

Application filed July 30, 1917. Serial No. 183,490.

To all whom it may concern:

Be it known that I, JAN LORENC, a citizen of Russia, residing at Philadelphia, in the county of Philadelphia and State of Pennsylvania, have invented certain new and useful Improvements in Ship-Buffers, of which the following is a specification.

This invention relates to certain new and useful improvements in ship's buffers.

10 The primary object of the invention is the provision of a buffer adapted to be carried by the hull of a ship adjacent the water line thereof for protecting the hull against collisions with other objects such as a boat 15 or wharf.

A further object of the invention is the provision of a plurality of buffer plates arranged in parallelism partially surrounding the hull of a ship, resilient mounting means 20 being provided whereby the shocks incident to striking an object will be absorbed and cushioned at the point of impact, while the hull carrying the device will not be injured.

With these general objects in view and 25 others that will appear as the nature of the invention is better understood, the same consists in the novel combination and arrangement of parts hereinafter fully described and illustrated in the accompanying drawings and then claimed.

30 In the drawing forming a part of this application and in which like reference characters designate corresponding parts throughout the several views,

35 Figure 1 is a top plan view of the hull of a ship provided with the present device.

Fig. 2 is a vertical sectional view through a portion of the device with a portion of the hull shown in elevation.

40 Fig. 3 is an enlarged elevational view of a portion of the hull and a portion of the device mounted thereon with parts of the device removed, and

Figs. 4 and 5 are sectional detail views 45 taken upon lines IV-IV and V-V of Fig. 2.

It will be understood that the device may be arranged upon any form of boat as a buffer therefor, the same being illustrated in 50 connection with a hull 10 of a ship having the device surrounding substantially the entire sides and bow portion 11 thereof but being interrupted at the stern portion 12 of the hull.

55 Elongated guideways 13 are secured upright upon the outer side 14 of the hull 10 in

parallelism and are provided with mounting blocks 15 slidably mounted therein adapted for receiving the inner ends of springs 16 within the sockets 17 of the said blocks, the 60 outer ends of said springs being seated within similar sockets 18 of suitable heads 19. Elongated strips or buffer plates 20 are secured to the outer faces of the head 19, whereby the said plates are arranged in 65 plurality substantially surrounding the entire hull 10 excepting its stern portion 12.

Each guideway 13 may be provided with a desirable number of buffer plates 20 in the manner herein described, four of the 70 same being herein illustrated as comprising the complete buffering device. It will be seen that by this arrangement the mounting guideways 13 and spring carried heads 19 may be spaced a suitable distance apart 75 while the forward ends 21 of the plates 20 are secured together in advance of the bow 11 of the hull 10 and at such point of connection there is preferably arranged a prow 22 of suitable material, preferably resilient, 80 such as rubber. A strip 23 may also be arranged within the points of attachment of the opposite plates 20 for connecting each row of plates together inwardly of the prow 22 while suitable springs 24 are arranged 85 between the strip 23 and a bow beam 25 upon the forward end of the bow 11.

Each vertical series of heads 19 is provided with a threaded connecting bar 26 passing through the said heads 19 and having adjusting nuts 27 threaded upon the bar at opposite sides of each head and whereby as will be apparent, the positions of the heads 19 upon the bars 26 may be readily adjusted and retained by means of the nuts 90 27. Retaining screws 28 are also provided for the blocks 15 for bearing against the guideways 13 and maintaining the blocks 15 against movement when suitably adjusted 95 relatively of the heads 19.

Pivoted struts 29 are arranged at the opposite ends of each rod 26, the said struts 29 being pivoted at their inner ends to brackets 30 secured to the hull 10 at points above and below the guideways 13, while the outer ends of the struts 29 are pivoted to collars 31 adjustably arranged upon the opposite ends of the rods 26 and retained in their required positions by means of lock nuts 32 threaded upon the end portions of 110 the rods 26.

A serviceable buffer for boats is arranged

capable of absorbing shocks at different levels, preferably adjacent the water line of the hull the construction being so arranged that an injury to one portion thereof will 5 have no effect upon the remainder of the device which will still be operative. Separate parts of the device may be easily adjusted while the structure as will be evident 10 may be carried by the hull of any form of boat for protecting the entire hull or any portion thereof.

What I claim as new is:—

1. In combination with a hull, upright guideways arranged in parallelism secured 15 to the hull, blocks adjustably arranged in the said guideways, outwardly projecting springs carried by the said blocks, heads upon the outer ends of the said springs, elongated strips carried by the said heads 20 in parallel superposed arrangement spaced from the side of the hull and adjustable connections between the said heads.

2. In combination with a hull, upright guideways arranged in parallelism secured 25 to the hull, blocks adjustably arranged in the said guideways, outwardly projecting springs carried by the said blocks, heads upon the outer ends of the said springs, elongated strips carried by the said heads in 30 parallel superposed arrangement spaced from the side of the hull, threaded rods passing through the said heads, retaining means between said heads and rods, and struts pivotally connected between the opposite ends of the said rods and the hull at 35 points removed from the opposite ends of the said guideways.

3. In combination with a hull, upright guideways arranged in parallelism secured to the hull, blocks adjustably arranged in the said guideways, outwardly projecting springs carried by the said blocks, heads upon the outer ends of the said springs, elongated strips carried by the said heads in parallel superposed arrangement spaced 45 from the side of the hull, a resilient prow connected between the forward ends of the said plates a strip arranged within said prow between the forward ends of said plates and springs arranged between the 50 said strip and the bow extremity of the hull. 4. In combination with a hull, upright guideways arranged in parallelism secured to the hull, blocks adjustably arranged in the said guideways, outwardly projecting 55 springs carried by the said blocks, heads upon the outer ends of the said springs, elongated strips carried by the said heads in parallel superposed arrangement spaced from the side of the hull, threaded rods 60 passing through the said heads, retaining means between said heads and rods, and struts pivotally connected between the opposite ends of the said rods and the hull at 65 points removed from the opposite ends of the said guideways, a resilient prow connected between the forward ends of the said plates a strip arranged within said prow between the forward ends of said plates and springs arranged between the said strip and 70 the bow extremity of the hull.

In testimony whereof I affix my signature.

JAN LORENC.
